CLAIM

The ornamental design for a cooking pot, as shown and described.

DESCRIPTION

FIG. 1 is a top, front, right-side perspective view of a cooking pot, showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a cross-sectional view taken along line 8-8 of FIG. 4; and,

FIG. 9 is a top, front, right-side perspective view thereof, shown in environmental use.

The broken lines in the figures illustrate the portions of the cooking pot and form no part of the claimed design. The broken line showing of a lid in FIG. 9 is for the purpose of illustrating environmental subject matter that forms no part of the claimed design.
